UNITED STATES PATENT OFFICE.

ELIZABETH JANE SMITH, OF LARCHMONT, NEW YORK.

SNAP-FASTENER.

1,360,459.

Specification of Letters Patent. Patented Nov. 30, 1920.

Application filed September 5, 1914. Serial No. 860,379.

To all whom it may concern:

Be it known that I, ELIZABETH J. SMITH, a citizen of the United States of America, residing in Larchmont, in the county of 5 Westchester and State of New York, have invented certain new and useful Improvements in Snap-Fasteners, of which the following is a specification.

This invention relates to snap fasteners, 10 and aims to provide improvements therein.

By the present invention, a simple, cheaply and readily manufactured, and efficient snap fastener is produced.

An embodiment of the snap fastener is 15 illustrated in the accompanying drawings, wherein—

Figure 1 shows a top plan view of a snap fastener in which the spring is applied, and

Fig. 2 is a vertical section of the parts 20 shown in Fig. 1;

Fig. 3 shows a spring embodying the invention.

Referring to the drawings, numeral 1 designates a socket member of a snap fastener 25 preferably formed of sheet metal, and 2 a bent spring of any suitable contour. The socket member is preferably provided with a socket 3 with slots 4 in the sides thereof through which portions of the spring are 30 adapted to project for engaging a ball-member inserted in the socket. Lugs 5 are preferably provided for holding the spring in place on the fastener.

In snap fasteners it is especially advantageous that the spring shall take up very little space on a face of the article, *i. e.*, it is desired that the spring shall "lie flat" upon the device.

The springs are preferably cut from thin 40 sheet metal, and are preferably of a width, somewhat greater than the thickness of the metal. A much stiffer spring, in propor-

tion to the thickness thereof, can be obtained by the present invention than by springs made from wire of corresponding 45 diameter.

The snap fasteners are preferably provided with elongated attaching prongs 8 which may be bent down and overlap laterally upon the top or back of the fastener, 50 clasping the goods against the back of the fastener. In such fasteners, a spring having a flat face is of especial advantage. The flat parts of the spring provide a greater contact surface for the goods than would be 55 the case for wire springs.

The inventive idea may receive other expressions than those illustrated and specifically referred to.

What is claimed is:—

1. A snap fastener having prongs adapted 60 to be bent down upon the back of the fastener, a socket having slots therein and a spring of flat sheet material having portions adapted to project through said slots. 65

2. A snap fastener having elongated prongs adapted to be bent down and overlap laterally upon the back of the fastener, a socket having slots therein and a spring of flat sheet material having portions adapted 70 to project through said slots.

3. A snap fastener having flat elongated prongs adapted to be bent down and overlap laterally upon the back of the fastener, a socket having slots therein and a spring of 75 flat sheet material having portions adapted to project through said slots.

In witness whereof, I have hereunto signed my name in the presence of two subscribing witnesses.

ELIZABETH JANE SMITH.
